FOUNTAIN COMB

William J. Kotsopoulos, Los Angeles, Calif.

Application July 20, 1937, Serial No. 154,642

2 Claims. (Cl. 132—13)

This invention relates to a fountain comb, designed for containing hair tonic, liquid hair dressing or medicine for the treatment of the scalp.

The primary object of the invention is to provide a comb of this character having a hollow head or container for containing the liquid to be used in treating the hair or scalp, there being provided openings for allowing the material to pass from the hollow head, to be distributed by the teeth of the comb.

An important object of the invention is to provide a device of this character having means whereby the discharge of the material used in the comb, may be regulated, so that the comb may be used in applying material of various consistencies.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawing:

Figure 1 is an elevational view of a comb constructed in accordance with the invention, a portion thereof being shown in section, illustrating the hollow head or chamber for containing the material fed by the comb.

Figure 2 is a sectional view taken on line 2—2 of Figure 1.

Figure 3 is a fragmental plan view of the comb.

Figure 4 is a fragmental plan view of the comb, the regulating plug thereof having been removed.

Referring to the drawing in detail, the reference character 5 designates the head of the comb, and the reference character 6 designates the teeth thereof.

As clearly shown by the drawing, the head of the comb is hollow, throughout a portion of its length, and is provided with an opening in which the headed screw 7 extends, the head of the screw, which is indicated by the reference character 8, being provided with an opening 9, adapted to register with the curved opening 10 formed in the bottom of the recessed portion of the head, in which the head 8 of the screw, normally lies. The opening 10, is of a construction, wide at one end and tapered towards the opposite end, so that when the head 8 is rotated to bring the opening 9 thereof into registry with the opening 10,

the size of the opening admitting air to the head of the comb, may be regulated to control the passage of material from the comb, by varying the quantity of air entering the hollow head of the comb.

Openings indicated by the reference character 11 are provided in the comb, and establish communication between the hollow portion of the comb and the atmosphere, the openings 11 being disposed between the teeth 6 of the comb, as clearly shown by Figure 1.

Lugs indicated by the reference character 12 are formed within the hollow portion of the head of the comb, and are formed with threaded openings to receive the threaded ends of the 15 guide pins 13, which are shown as positioned therein. The reference character 14 designates a plate, which is of a length adapted to extend throughout substantially the entire length of the hollow portion of the head of the comb, the plate 20 being formed with openings to accommodate the pins 13 whereby the plate 14 will be guided in its vertical movement.

Secured to the plate, is a member indicated by the reference character 15, the member being 25 constructed preferably of rubber so that when the member 15 is moved downwardly against the bottom of the hollow portion of the head of the comb, the openings 11 will be closed, so that the material contained in the hollow portion of 30 the head of the comb will be held against discharging through the openings 11.

Coiled springs indicated by the reference character 16 surround the enlargement 12, and contact with the lower surface of the plate 14, normally urging the plate and member 15 upwardly.

The screw 7, is of a length to contact with the plate 14, to adjust the plate and member 15, with respect to the openings 11 to regulate the quantity of material passing from the opening.

In the use of the device, the member 15 is adjusted so that the material contained in the hollow portion of the comb may pass through the openings 11, and may be distributed over the scalp of the head under treatment. The comb 45 may now be reversed and the teeth at the opposite end of the comb may be used in combing the hair to spread the material.

It might be further stated that the plug 8 is formed with a slot 17 for the reception of a coin 50 or tool by means of which the plug may be rotated in a manner as described.

Openings 18 are formed in the member 15, the openings 18 registering with certain of the openings 11, so that a wire or similar device may be 55

inserted into the openings 18 moving the member 15 away from the openings 11, should the member 15 adhere to the bottom of the hollow portion of the comb.

5 Having thus described the invention, what is claimed is:

1. A fountain comb comprising a head having a hollow portion, teeth extending from the head, said head having discharge openings through which material passes from the hollow head, a movable member in the hollow portion of the head and adapted to move to close the discharge openings, said head having an opening through which air passes to the hollow head displacing liquid discharged from the hollow head, a headed screw having an opening registering with the last mentioned opening and adapted to regulate the size of the air inlet openings, controlling the passage of material from the hollow portion of the 20 head, and said screw adapted to move the mov-

able member to a position closing the discharge openings.

2. A fountain comb comprising a head having a hollow portion, teeth extending from the head, said head having openings through which material passes from the hollow head, a member operating in the hollow head and adapted to move to close the openings, said member adapted to be adjusted with respect to the openings, adapting the comb for use in distributing material of 10 various consistencies, means for normally urging the member away from the openings whereby material may pass from the hollow head, said head having an opening admitting air to the hollow portion thereof, a member having an 15 opening adapted to register with the latter opening whereby air is admitted to the hollow head, controlling the flow of material from the head.

WILLIAM J. KOTSOPoulos. 20
